We claim the ornamental design for a stand for television receiver, as shown and described.

DESCRIPTION

FIG. 1 is a front perspective view of a stand for television receiver showing our new design;
 FIG. 2 is a bottom perspective view thereof;
 FIG. 3 is a front elevation view thereof;
 FIG. 4 is a rear elevation view thereof;
 FIG. 5 is a left-side elevation view thereof;
 FIG. 6 is a right-side elevation view thereof;
 FIG. 7 is a top plan view thereof;
 FIG. 8 is a bottom plan view thereof;
 FIG. 9 is a perspective view of the stand for television receiver shown in a state of use; and,
 FIG. 10 is another perspective view thereof.

The broken lines shown in FIGS. 1 to 8 represent portions of the stand for television receiver that form no part of the claimed design. The broken lines showing of the display screen in FIGS. 9 and 10 is for the purpose of illustrating environment and form no part of the claimed design.
